UNITED STATES PATENT OFFICE.

VANDIVER J. VAN HORN, OF CHICAGO, ILLINOIS, ASSIGNOR TO UNION SPECIAL
MACHINE COMPANY, OF CHICAGO, ILLINOIS, A CORPORATION OF ILLINOIS.

SEAM FOR SEWED ARTICLES.

1,100,510.

Specification of Letters Patent. Patented June 16, 1914.

Application filed February 13, 1911. Serial No. 608,380

To all whom it may concern:

Be it known that I, VANDIVER J. VAN HORN, a citizen of the United States, residing at Chicago, in the county of Cook, State of Illinois, have invented certain new and useful Improvements in Seams for Sewed Articles, of which the following is a description, reference being had to the accompanying drawing and to the letters and figures of reference marked thereon.

My invention relates to new and useful improvements in ornamental seams for sewed articles, and has for an object to provide a fabric with a plurality of substantially parallel lines of stitching, and an ornamental thread which extends back and forth from one line of stitching to the other, which thread is formed into a series of loops lying along one line of stitching and secured thereby.

In the drawings,—Figure 1 is a plan view showing a fabric having said improved seam embodied therein; and Fig. 2 is an enlarged detail, showing the construction of said seam.

The fabric A is provided with two lines of stitching 1 and 2, which, as herein shown, are substantially parallel. The line of stitching 1 is produced by the needle punctures 3, 3, while the line of stitching 2 is produced by the needle punctures 4, 4. An ornamental thread 5 extends from one line of stitching to the other, as at 6, and then encircles a needle puncture 4, and again crosses from one line of stitching to the other, as at 7. The portion of the ornamental

thread 5 extending outside of the line of stitching 1 is formed into a long loop 8. Said loop 8 is given a half twist, so as to cross the strands thereof, as at 9. The loop 8 is laid along the line of stitching 1, and is entered by a needle puncture 3. The loop 8 extends underneath the ornamental thread 7. The ornamental thread extends underneath the needle threads forming the lines of stitching 1 and 2.

Having thus described my invention, what I claim as new and desire to secure by Letters Patent, is:—

1. An ornamental seam for sewed articles, including a fabric, two substantially parallel lines of stitching, and an ornamental thread extending back and forth from one line of stitching to the other, said thread at one line of stitching being formed into loops, which are laid along said line of stitching and secured thereby.

2. An ornamental seam for sewed articles including a fabric, two substantially parallel lines of stitching, and an ornamental thread extending back and forth from one line of stitching to the other, the portion of said ornamental thread outside of one line of stitching being formed into loops which are half twisted, said loops being laid along said line of stitching and secured thereby.

In testimony whereof I affix my signature in presence of two witnesses.

VANDIVER J. VAN HORN.
